CONTROL APPARATUS

Walter P. Wills, Philadelphia, Pa., assignor to The Brown Instrument Company, Philadelphia, Pa., a corporation of Pennsylvania

Application April 27, 1940, Serial No. 332,119

38 Claims. (Cl. 158—28)

The present invention relates to combustion control systems for fuel burners.

An object of the invention is to provide a combustion control system which operates in accordance with a characteristic of the fuel burner flame.

Another object of the invention is to provide a combustion control system embodying safety control provisions which operates in accordance with a characteristic of the fuel burner flame.

A further object of the invention is to provide a safety control system for a fuel burner which relies in its operation upon the characteristic fluctuating conductance of burner flames.

A still further object of the invention is to provide a safety control system for a fuel burner which employs a pair of electrodes in engagement with the burner flame and which is sensitive to the presence of a flame between the electrodes but is insensitive to other conductive paths therebetween.

A further object of the invention is to provide a control system for controlling the quality or extent of combustion in a fuel burner which relies in its operation upon the conductance between a pair of electrodes in engagement with the burner flame and otherwise insulated from each other.

A still further object of the invention is to provide a control system for controlling the quality or extent of combustion in a fuel burner which relies in its operation upon the characteristic fluctuating conductance of burner flames.

Another object of the invention is to provide a combined combustion quality and safety control system for a fuel burner which relies in its operation upon the conductance between a pair of electrodes in engagement with the burner flame and otherwise insulated from each other.

A further object of the invention is to provide a combined combustion quality and safety control system for a fuel burner which relies in its operation upon the characteristic fluctuating conductance of burner flames.

In combustion control systems which have been proposed heretofore, various means have been employed for determining if combustion conditions are proper, and whether combustion actually takes place, one such means comprising an electrode which extends into the flame of the burner and which is so connected in the system as to provide a conductive path of relatively low resistance to ground through the flame. The variation in the electrical conductivity of this path to ground when a flame is present and when

a flame is not present is commonly employed to change the bias on the control grid of an electronic valve for controlling a thermal safety switch. Since there is a possibility that a low resistance path may be set up from the electrode to ground through other agencies than by means of the flame, for example, a low resistance path which may be established between the flame electrode and ground by reason of carbonization, by accidental touching of the electrode to ground, or by other abnormal conditions simulating combustion, provisions have been made in devices of the prior art for preventing the fuel supply and ignition from being turned on when such abnormal conditions exist.

Since an abnormal condition of this character simulating combustion may arise after the system is already in operation, it is desirable to provide means for distinguishing between such abnormal conditions and natural combustion while the system is in operation. For example, in a thermostatically controlled house heating system, if the control system is insensitive to the presence of the flame after initial ignition of the flame, the fuel feeding means will be operated continuously as long as the room thermostat is closed. If the flame should then be extinguished, the furnace will be flooded with atomized fuel and a highly explosive mixture of the latter will be permitted to accumulate.

Various means, independent of safety control means have been provided in the prior art for determining the quality of combustion in a burner, that is for determining the degree of combustion of the fuel, and for controlling the mixture of fuel and air to the burner so as to secure optimum combustion conditions.

I have discovered that the conductance of a flame is not constant in magnitude, but is continuously fluctuating. In addition I have discovered that the amplitude of the fluctuations varies inversely with the degree of combustion of the burning fuel. That is to say, the amplitude of fluctuation of the flame conductance is larger when the flame is yellow, containing a large quantity of unburned carbon particles, and smaller when the flame is blue, indicating that combustion of the burning fuel is more nearly complete.

Advantage of these characteristics is taken in the device of my present invention, which device relies in its operation on the fluctuating character of the flame conductance to detect the presence of a flame and is responsive to the amplitude of the flame conductance fluctuations to provide

a measure of the quality or degree of combustion of the burning fuel.

The various features of novelty which characterize my invention are pointed out with particularity in the claims annexed to and forming a part of this specification. For a better understanding of the invention, however, its advantages and specific objects obtained with its use, reference should be had to the accompanying drawings and descriptive matter in which I have illustrated and described a preferred embodiment of the invention.

Of the drawings:

Fig. 1 is a schematic diagram of a preferred embodiment of my safety combustion control system as applied to a fuel burner; and

Figures 2, 3, 4, 5 and 6 show various modifications of the flame responsive circuit of my invention, which circuit may be used to operate either a safety control system or a combustion control system, or both.

Figure 1 of the drawings shows a gas burner 1 supplied with gas through conduit 2 and the flow of gas to the burner is controlled by an electrically operated or other suitable valve 3. A pilot burner 4 is provided which is controlled by an electrically operated or other suitable valve 5, and means are provided for igniting the pilot flame including a pair of electrodes 6 which are connected to the terminals of a secondary winding 7 of an ignition transformer 8 having a primary winding 9 which is adapted to be energized from the alternating current supply lines L¹ and L².

The fuel valve operating circuit of my control system is controlled by means of a thermostat 10 which may be located in a room or space to be heated. The thermostat 10 may be of any suitable construction and includes a bimetallic element 11 connected by means of conductor 12 to line L², and a contact blade 13 adapted to engage a stationary contact 14 which is connected to line L¹ through a thermal switch 15 and winding 16 of a transformer 17.

The thermal switch 15 is preferably of the form disclosed in the Patent 1,958,081, issued to F. S. Dennison, May 8, 1934. As shown more or less diagrammatically in the drawings, this switch comprises a stationary arm 18 and a movable arm 19 biased for movement away from arm 18 but normally held in engagement with the latter by means of a bimetallic element 20. Element 20 is rigidly secured at one end to a block 21 and is arranged to be heated by a coil 22 when the latter is energized through a circuit which will later be described. Upon energization of coil 22 for a predetermined period of time, element 20 will be warped sufficiently in the clockwise direction to permit arm 19 acting under spring or other bias to separate from switch arm 18 thereby interrupting the circuit including thermostat 10. The switch 15 will remain locked in this position until manually returned to its normal closed position.

Both the main burner 1 and the pilot burner 4 are supplied with a combustible mixture of fuel and air from the mixing chamber 23 into which fuel is introduced through conduit 24, and air through conduit 25. The amount of air passing through the conduit 25 is controlled by an electrically operated, or other suitable valve 26 which is adapted to be energized from the alternating current supply lines L¹ and L².

The transformer 17 which supplies power for

the control system comprises the primary winding 16 and the secondary winding 27, having terminals 28 and 29 and a center tap 30. The portion of the secondary winding 27 between terminal 28 and center tap 30 serves as a source of energy for an electric discharge device 31, hereinafter referred to for convenience as the rectifier. The rectifier 31 may be of any suitable type, being shown in the drawings as a triode comprising an anode 32, a control electrode 33, a cathode 34, and a heater filament 35. Control electrode 33 is shown connected to cathode 34, so that the triode acts substantially as a diode. The rectifier 31 is adapted to charge a condenser 36, which is shunted by a resistance 38A, during the half-cycles when it is conductive, and the condenser 36 and resistance 38A are so proportioned that a substantial part of the charge is maintained on the condenser during alternate half-cycles, thus maintaining between its terminals a unidirectional potential, polarized as shown in the drawings. This charging circuit may be traced from center tap 30 of transformer secondary winding 27, through a conductor 37, condenser 36, and rectifier 31 to terminal 28 of the transformer winding. The center tap 30 is connected to ground as at 38.

The potential which is maintained by the condenser 36 supplies a circuit, hereinafter termed the detector output circuit, through a second electric discharge device 39, hereinafter referred to as the detector. The detector 39 is shown as a triode comprising an anode 40, a control electrode 41, a cathode 42, and a heater filament 43. The detector output circuit may be traced from the positive terminal of condenser 36, through conductor 37, a resistor 44, anode 40, cathode 42, a cathode biasing resistor 45, and a conductor 46 to the negative terminal of condenser 36. Control electrode 41 is connected through a condenser 47 and a conductor 48 to an electrode 49 which projects into the flame of the pilot burner 4. The conductor 48 is preferably encased within a shield 50, which is grounded, as at 51. The control electrode 41 is also connected through a resistor 52 to the conductor 46. The conductor 48 is connected through a resistor 53 to the conductor 46. The difference of potential between the control electrode 41 and the cathode 42 is controlled by a circuit, hereinafter termed the detector input circuit, which may be traced from the positive terminal of condenser 36, through conductor 37, ground connection 38, a ground connection 54, pilot burner 4, the conductance, if any, existing between the burner and the flame electrode 49, the flame electrode, conductor 48, resistor 53 in parallel with condenser 47 and resistor 52, and conductor 46 to the negative terminal of condenser 36. As noted, the control electrode 41 is connected to the common terminal of condenser 47 and resistor 52.

When there is a path of constant conductance between electrode 49 and burner 4, all the current traversing that path will pass through the resistor 53 because the condenser 47 will not pass direct current. There will, therefore, be no transfer of energy through the condenser 47 and accordingly the control electrode 41 will be at the same potential as conductor 46. Detector 39 will then be conductive. These conditions will obtain regardless of the value of the constant conductance, that is, regardless of whether it is

nitude (grounded flame electrode conditions), or some intermediate value.

When a flame exists between electrode 49 and burner 4, however, the current traversing the flame will fluctuate in accordance with the varying conductance of the flame. This current may be considered as composed of a constant direct component and a superimposed fluctuating component. The condenser 47 will pass the fluctuating component, and a fluctuating potential will thereby be produced across the resistor 52. This fluctuating potential is applied to the control electrode 41 and operates to vary the flow of current in the output circuit of the detector 39 at the frequency of said fluctuating potential.

The potential difference established across the resistor 44 by the varying current flow in the detector output circuit is used to control a third electric discharge device 55, hereinafter referred to as the amplifier, and shown as a triode comprising an anode 56, a control electrode 57, a cathode 58, and a heater filament 59. This control operation is effected through the amplifier input circuit which may be traced from amplifier grid 57, conductor 60, resistor 44, through conductor 37 and cathode 58. The amplifier 55 is supplied with energy by that portion of the transformer secondary winding 27 between terminal 28 and center tap 30, and controls the flow of current through an output circuit which may be traced from terminal 28, through a conductor 61, a relay winding 62 having a condenser 63 connected in parallel therewith, another relay winding 64 having a condenser 65 connected in parallel therewith, anode 56, cathode 58, and conductor 37 to center tap 30.

The relay winding 62 comprises a part of a relay 66, which also includes switch arms 67 and 68, cooperating with front contacts 69 and 70, respectively. The switch arm 68 is spring biased to engage with a back contact 71. The term "front contact" is used to indicate a contact on which a switch arm is closed when its associated relay winding is energized, and "back contact" indicates one on which a switch arm is closed when its relay winding is de-energized. The relay winding 64 comprises a part of a relay 72, which also includes a switch arm 73, cooperating with a front contact 74 and a back contact 75. The switch arm 73 is biased to close on its back contact 75 by a spring 77 and is adapted to be moved against that bias force and against the opposing force of a compression spring 79 into engagement with contact 74. If the current flow through the relay winding 64 gradually increases from zero, it first overcomes the opposing bias of spring 77, and pulls arm 73 down until it engages spring 79. The spring 79 then balances the attraction of the relay winding and holds the switch arm 73 separated from both its front and back contacts. If the current flow through winding 64 continues to increase, it eventually becomes sufficient to overcome the opposing effect of both springs 77 and 79, and closes switch arm 73 on its front contact 74. By adjusting the tension on the spring 77 and the compression of spring 79, the current levels at which these two actions of relay 72 take place may be adjusted as desired.

As previously explained, when a path of constant conductance exists between electrode 49 and burner 4, detector 39 is conductive. The potential difference across resistor 44 produced by this current makes control electrode 57 negative with respect to cathode 58, and maintains

amplifier 55 substantially non-conductive. When a flame exists between electrode 49 and burner 4, however, detector 39 is intermittently rendered non-conductive, and as a result, the potential of the control electrode 57 is intermittently substantially the same as the potential of cathode 58. Amplifier 55 will then be intermittently conductive during the half cycles when the anode 56 is positive with respect to the potential of cathode 58. It is noted the frequency of the fluctuations of the flame conductance is greater than that of the current supplied by the transformer (the latter being of commercial frequency, for example, 25 or 60 cycles). The condensers 63 and 65 are provided to smooth out the pulsating current which is passed by the amplifier 55, and thereby stabilizes the action of their associated relays. The relay 66 is designed to pick up its switch arm substantially as soon as the amplifier 55 becomes conductive. The relay 72 is designed to open the circuit through its back contact 75 when the current flow reaches a predetermined level, and to close the circuit through its front contact 74 when the current reaches a predetermined higher level, as explained previously herein.

When the temperature of the room or space to be controlled falls below the value it is desired to maintain, the thermostat 10 operates to move the switch blade 13 into engagement with the stationary contact 14, thus completing energizing circuits for the transformer primary 16, the ignition transformer primary 9, and the pilot burner valve 5. The energizing circuit for the ignition transformer primary 9 may be traced from line L² through thermostat 10, thermal switch 15, a conductor 80, switch arm 68, back contact 71, a conductor 81, and winding 9 to line L¹. The energizing circuit for pilot burner valve 5 may be traced from line L² through thermostat 10, thermal switch 15, heater coil 22, a conductor 82, valve 5, and a conductor 83 to line L¹. The energizing circuit for transformer primary 16 has been previously traced. The heater filaments 35, 43 and 59 of valves 31, 39 and 55, respectfully, are preferably energized from a separate secondary winding (not shown) on the transformer 17. Therefore, the valves 31, 39 and 55, will be rendered operative after a short time delay required for the filaments to heat upon engagement of the thermostat contact arm 13 and contact 14.

The normal result of the opening of the pilot burner valve and the energization of the ignition transformer will be the appearance of a flame at the pilot burner. The presence of a flame at the pilot burner acts through the detector and amplifier circuits, as previously described, to energize relay winding 62, causing switch arm 68 to close on front contact 70, and switch arm 67 to close on front contact 69. This de-energizes the ignition transformer 9 by opening its circuit at contact 71, energizes the main burner valve 3, and shunts the heater coil 22 from the circuit of pilot burner valve 5. The energizing circuit for the valve 3 may be traced from line L² through thermostat 10, thermal switch 15, conductor 80, switch arm 68, contact 70, a conductor 84, valve 3, and conductor 83 to line L¹. The heater coil 22 is shunted through a conductor 85, contact 69, and switch arm 67. The safety control system is then in full normal operation.

If a flame does not appear when the pilot burner valve and the ignition transformer are

energized, the heater winding 22 of thermal switch 15 will remain energized, and will, after a predetermined time, open the switch 15 and thereby de-energize the entire system.

If the flame becomes extinguished after the system has attained full operation, the relay winding 62 will be de-energized thus opening the circuit at contact 70 to the main burner valve 3 and thereby effecting closure of the latter, energizing the ignition transformer primary 9, and opening the shunt around heater winding 22. If a flame thereafter reappears, the system will again go into full operation, but if a flame does not appear within a predetermined time, the thermal safety switch 15 will operate to deenergize the entire system.

The air controlling valve 26 is operated by a reversible motor (not shown) which is energized for rotation in one direction through a circuit which may be traced from line L² through conductor 86, switch arm 73, contact 75, conductor 87, valve 26 and conductors 89 and 83 to line L¹ and is energized for rotation in the opposite direction through a circuit which may be traced from line L², conductor 86, switch arm 73, contact 74, conductor 88, valve 26, conductors 89 and 83 to line L¹. The motor is adapted to close the valve when it is energized through contact 75 and conductor 87, and to open the valve when energized through contact 74 and conductor 88. The valve 26 is provided with a limit switch (not shown) which operates to open conductor 87 and thereby deenergize the motor when the valve has been adjusted to its closed position. The limit switch is preferably so adjusted that the valve can never be completely closed. A second limit switch (not shown) is also provided for opening conductor 88 and thereby deenergizing the motor when the valve 26 has been fully opened.

When the system operation is first initiated, the switch arm 73 will be in the position shown, the valve 26 will be at its minimum opening, and the fuel mixture will accordingly be rich. This will result in the establishment of a yellow flame having a conductance which fluctuates widely, whereby the effective current value in the amplifier output circuit and thereby through relay winding 64 will be sufficient to close the switch arm 73 against contact 74. This will energize the motor of valve 26 in the direction to open the valve. As the valve opens, more air is supplied and accordingly, combustion becomes more complete. The amplitude of the flame conductance variation decreases, and hence the current through relay winding 64 decreases, until it reaches a value at which springs 77 and 79 bias switch arm 73 away from contact 74, but maintains it out of engagement with contact 75. The fuel mixture will then have its proper proportions, and the valve setting will remain constant until some change in fuel quality, for example B. t. u. content, or pressure, or the like, causes a change in the amplitude of flame conductance fluctuation outside the range for which the device is adjusted.

It will be clear from the foregoing explanation that the combustion control system described controls a fuel burner in accordance with the presence or absence of a flame, and also controls the proportions of the fuel mixture so as to obtain efficient combustion. Moreover, as will be apparent to those skilled in the art, either of these functions may be obtained without the other.

In Fig. 2 I have illustrated, more or less diagrammatically, a modified detector and amplifier circuit embodying my invention, in which the use of a separate rectifier is obviated by combining

5 in a single triode the functions of the rectifier and detector. Fig. 2 also shows a modified relay system, in which a single relay 66A performs all the functions of relays 66 and 72 of Fig. 1. Parts in Fig. 2 which are the equivalents of corresponding parts in Fig. 1 have been given the same numerals.

In Fig. 2 the triode 39 acts as both rectifier and detector in the circuit. The rectifier circuit is the same as the detector output circuit and may be traced from transformer center tap 30 through conductor 37, resistor 44, anode 40, cathode 42, resistor 36A and condenser 36 in parallel to the transformer secondary winding terminal 29. Current pulses through this circuit during the 10 half cycles when the anode is positive, and builds up a charge on condenser 36 such that its terminals have the polarity shown in the drawings. The detector input circuit comprises the same elements as in Fig. 1, but functions in a slightly 15 different manner, due to the fact that cathode 42 is connected to the positive terminal of condenser 36 rather than to the negative terminal. The flame conductance in this circuit is in parallel with a circuit including condenser 47 and 20 resistor 52 in series, between one end of resistor 53 and the grounded positive terminal of condenser 36. When the conductance between electrode 49 and the grounded burner is constant, the potential across condenser 47 is also 25 constant, and no current passes through it. Control electrode 41 of valve 39 remains, therefore, at substantially cathode potential. When a flame exists between electrode 49 and ground, however, its conductance varies, and a variable potential 30 is impressed across condenser 47. A fluctuating current then flows through the condenser, causing a fluctuating potential difference across resistor 52 and intermittently reducing the output 35 of detector 39. The detector, therefore, responds to flame conditions in the same way that the detector of the Fig. 1 arrangement responds to 40 flame conditions.

The relay 66A in Fig. 2 operates all the switch 45 arms for the combustion and safety control system of Fig. 1. Each switch arm and contact has been given the same reference numeral as in Fig. 1, with the letter A added. The back contact 75A and the front contacts 69A and 70A are mounted on springs 75B, 69B and 70B, respectively.

When the average current flowing through relay winding 62A is below a certain level, for example, 10 milliamperes, the winding is not energized sufficiently to lift its armature, and the switch arms are in the position shown in the drawings. As the current increases above 10 m. a., the winding is energized sufficiently to close switch arms 67A and 68A against contacts 69A and 70A, respectively. Contact 75A, moved by compression spring 75B, follows switch arm 73A and remains in engagement with it. If the current in winding 62A continues to increase beyond, say 20 m. a., the switch arms are moved further upward, as they appear in Fig. 2, compressing springs 69B and 70B and raising switch arm 73A beyond the upper limit of movement of contact 75A and into engagement with spring 79A. Since there are now three springs, 69B, 70B, 55 and 79A, opposing further upward motion of the

armature, the current in relay winding 62A must increase still more, say, above 30 m. a., in order to bring switch arm 73A into engagement with contact 74A.

It may be seen, therefore, that the switch arms 67A and 68A have one of two alternative positions, dependent upon the relay current being greater or less than 10 m. a., in the given example, and that the switch arm 73A may take up any of three positions corresponding to the illustrative relay currents ranges of 0-20, 20-30, and over 30 m. a., respectively. It should be apparent to those skilled in the art that these current ranges may be adjusted to any desired value by adjusting the spring tensions.

In Fig. 3 I have illustrated another modification of the arrangement of Fig. 1 wherein safe failure of the system is obtained on failure of the detector and wherein the potential of the flame electrode 49 is maintained positive with respect to the burner potential. The negative terminal of condenser 36 is grounded in this modification, thus making the flame electrode 49 positive with respect to the burner and to ground. It is known that flames possess a rectifying characteristic, that is to say, the conductivity of the flame is greater in the direction opposite to the direction of the flame propagation. The use of a positively biased flame electrode takes advantage of this characteristic. It is desirable to take advantage of this characteristic in that the position of the flame electrode in the path of the flame is less critical than when the flame electrode is negative in potential relatively to the burner as in the Figs. 1 and 2 arrangement. That is to say, the position of the flame electrode may then be adjusted considerably with respect to the flame without affecting the circuit operation.

In Fig. 3 I have also illustrated the use of a power amplifier whereby more positive operation of the relays 66 and 72 is obtained thereby permitting the use of heavier and more rugged relays.

The triode amplifier 55 of the previous circuit arrangement has been replaced in Fig. 3 by a tetrode 91 having an anode 92, a screen electrode 93, a control electrode 94, a cathode 95 and a heater filament 96. The amplifier output circuit may be traced from terminal 28 of the transformer secondary winding 27 through a conductor 97, relay winding 62 in parallel with condenser 63, relay winding 64 in parallel with condenser 65, anode 92, cathode 95, and a conductor 98 to tap 30 which in this circuit is closely adjacent terminal 29 of the secondary winding. The screen electrode 93 is connected through a resistor 99 to the conductor 97. The control electrode 94 is connected to the negative terminal of resistor 44 through a condenser 100, and to the terminal 29 of the transformer secondary winding 27 through a resistor 101. The latter connection is provided to bias the control electrode 94 negatively during the half cycles of the supply voltage when the anode 92 is positive so that amplifier 91 will be non-conductive in the absence of an impulse supplied through condenser 100, which condenser serves to isolate control electrode 94 from constant potentials existing in the detector circuit. The normal grid-biasing voltage is therefore supplied independently of the detector circuit in this modification, and in case of failure of the detector, the amplifier output would be cut off, thus causing the system to cease operation. This is a partic-

ularly desirable feature, especially, in the safety control system, as it would prevent operation of the system with a defective detector circuit.

In Fig. 4 I have illustrated a modification of the circuit arrangement of Fig. 3 in which the condenser 47 has been dispensed with and the functions thereof are performed by the condenser 100. Fig. 4 differs further from Fig. 3 in that a negative flame electrode is employed. The detector input circuit in Fig. 4 may be traced from the positive condenser 36 through conductor 37, ground 38, ground 54, pilot burner 4, the flame conductance, flame electrode 49 and resistances 102 and 52 in series to the negative terminal of condenser 36. Control electrode 41 is connected to the common terminal of resistor 102 and 52. When the conductance between electrode 49 and pilot burner 4 is constant, the potential of control electrode 41 and the output of detector 39 are also constant, and no current passes through condenser 100 to the control electrode 57 of amplifier 55. When a flame exists between electrode 49 and burner 4, its varying conductance causes a like variation in the potential of control electrode 41 and in the output of detector 39, which is transmitted through condenser 100 to the control electrode 57 of amplifier 55. A condenser 103 is provided in shunt with the cathode biasing resistor 45 in Fig. 4 in order to stabilize the potential across that resistor when the detector output is fluctuating. The resistor 102 is provided to limit the flow of current between the control electrode 41 and cathode 42 upon the accidental occurrence of the flame electrode 49 becoming grounded.

Fig. 5 illustrates a modified detector and amplifier circuit which employs a single electronic tube of the duplex-diode triode type, numbered 104 in the drawings, having an anode 105, a control electrode 106, and a cathode 107, two diode anodes 108 and 109 and a heater filament 110. The elements 105 and 106 and 107 function as a triode and the diode anodes 108 and 109 cooperate with the cathode 107 to form a half wave rectifier the circuit of which may be traced from tap 30 of the transformer secondary winding 27, through a conductor 111, diode anodes 108 and 109, cathode 107, resistor 45, and resistor 90 and condenser 36 in parallel to terminal 29 of transformer secondary 27. The input circuit of the triode, which functions as both detector and amplifier in this modification, is the same as that for detector 39 in the circuit of Fig. 2, except that the potential difference across resistor 45, caused by current flow in the rectifier circuit, is utilized to bias control electrode 106 negatively with respect to cathode 107. This bias potential is applied through resistor 52, and operates to maintain the triode nonconductive except when a fluctuating potential is superimposed upon it or in other words a flame exists between electrode 49 and ground.

Fig. 6 illustrates a modification of the circuit of Fig. 5, in which the position of the resistor 90 and the condenser 36 has been changed from the cathode side of the rectifier to the anode side, and which may be more desirable than the circuit of Fig. 5 for some types of electronic tubes.

It will be readily understood by those skilled in the art that the relay arrangements of Figs. 1 and 2 are interchangeable, and that either one may be used in any of the circuits shown.

While in accordance with the provisions of the statutes, I have illustrated and described the best form of my invention now known to me, it will

be apparent to those skilled in the art that changes may be made in the form of the apparatus disclosed without departing from the spirit of my invention as set forth in the appended claims, and that in some cases certain features of my invention may sometimes be used to advantage without a corresponding use of other features.

Having now described my invention, what I claim as new and desire to secure by Letters Patent is:

1. A combined safety and quality control system for a fuel burner including fuel and air supply means, igniting means to establish a flame at said burner, a device to control said fuel supply means, and means to control the mixture of fuel and air supplied to said burner comprising in combination, a pair of spaced electrodes insulated from each other and positioned in the path of said flame, and means connected to said electrodes and responsive to the conductance of the path therebetween to control said control device and said mixture control means.

2. A combined safety and quality control system for a fuel burner including fuel and air supply means, igniting means to establish a flame at said burner, a device to control said fuel supply means, and means to control the mixture of fuel and air supplied to said burner comprising in combination, a pair of spaced electrodes insulated from each other and positioned in the path of said flame, a device to operate said fuel supply control device, a device to operate said mixture control means, and means connected to said electrodes and responsive to the conductance of the path therebetween to control said operating devices.

3. A combined safety and quality control system for a fuel burner including fuel and air supply means, igniting means to establish a flame at said burner, a device to control said fuel supply means, a valve to control the mixture of fuel and air supplied to said burner, and a device to operate said valve comprising in combination, a pair of spaced electrodes insulated from each other and positioned in the path of said flame, a current responsive device to operate said first mentioned device, a current responsive device to operate said second mentioned device and having an operating characteristic such that when energized with current of a predetermined range it actuates said second mentioned device to open said valve and when energized with current of a different predetermined range it actuates said second mentioned means to close said valve, and means adapted to be connected to a source of electrical energy and to said electrodes and responsive to the conductance of the path between said electrodes to control the energization of said current responsive devices.

4. A combined safety and quality control system for a fuel burner including fuel and air supply means, igniting means to establish a flame at said burner, a device to control said means having two operating conditions one permitting and the second preventing establishment of a flame at the burner, and means to control the mixture of fuel and air supplied to said burner comprising in combination, a pair of spaced electrodes insulated from each other and positioned in the path of said flame, a current responsive device to operate said control device and adapted when energized to actuate said control device to its first mentioned operating condition and adapted when deenergized to actuate said con-

trol device to its second mentioned operating condition, a current responsive device to operate said mixture control means, and means adapted to be connected to a source of electrical energy and to said electrodes and responsive to the conductance of the path between said electrodes to control said current responsive devices.

5. A safety control system for a fuel burner including means to establish a flame at said burner and a device to control said means comprising in combination, a pair of spaced electrodes insulated from each other and positioned in the path of said flame, a device for operating said control device, a circuit adapted to connect said operating device to a source of electrical energy, and means to control the conductivity of said circuit in response to fluctuations in the conductance between said electrodes, said last mentioned means being insensitive to steady values of conductance between said electrodes.

6. A safety control system for a fuel burner including means to establish a flame at said burner, and a device to control said means comprising in combination, a pair of spaced electrodes insulated from each other and positioned in the path of said flame, a current responsive device for operating said control device and adapted when energized to actuate said control device to permit the establishment of a flame at said burner and adapted when deenergized to actuate said control device to prevent the establishment of a flame at said burner, means adapted to connect said current responsive device to a source of electrical energy including an electric discharge device having an input circuit and an output circuit in which said current responsive device is connected, and means to control the input circuit of said discharge device in response to fluctuations in the conductance between said electrodes, said last mentioned means being insensitive to steady values of conductance between said electrodes.

7. A safety control system for a fuel burner including means to establish a flame at said burner, and a device to control said means comprising in combination, a pair of spaced electrodes insulated from each other and positioned in the path of said flame, a current responsive device for operating said control device and adapted when energized to actuate said control device to permit the establishment of a flame at said burner and adapted when deenergized to actuate said control device to prevent the establishment of a flame at said burner, means adapted to connect said current responsive device to a source of electrical energy including an electric discharge device having an input circuit and an output circuit in which said current responsive device is connected, and a connection between said electrodes and the input circuit of said discharge device including a reactance to control said input circuit in response to fluctuations in the conductance between said electrodes, said last mentioned connection being insensitive to steady values of conductance between said electrodes.

8. A combustion quality control system for a fuel burner including fuel and air supply means, igniting means to establish a flame at said burner, and a device to control the mixture of fuel and air supplied to said burner comprising in combination, a pair of spaced electrodes insulated from each other and positioned in the path of said burner flame, a device for operating said control device, a circuit adapted to connect

said second mentioned device to a source of electrical energy, and an electric discharge device having an output circuit connected in said first mentioned circuit and an input circuit controlled by fluctuations in amplitude of the conductance between said electrodes but insensitive to steady values of said conductance.

9. A combustion quality control system for a fuel burner including fuel and air supply means, igniting means to establish a flame at said burner, a valve to control the mixture of fuel and air supplied to said burner, and a device to operate said valve comprising in combination, a pair of spaced electrodes insulated from each other and positioned in the path of said burner flame, a current responsive device to operate said first mentioned device and having an operating characteristic such that when energized with current of a predetermined range it actuates said first mentioned device to open said valve, when energized with current of a second and different predetermined range it actuates said first mentioned device to maintain said valve stationary, and when energized with current of a third and different predetermined range it actuates said first mentioned device to close said valve, a circuit adapted to connect said current responsive device to a source of electrical energy, and an electric discharge device having an output circuit connected in said first mentioned circuit and an input circuit controlled by fluctuations in amplitude of the conductance between said electrodes but insensitive to steady values of said conductance.

10. In combination, fuel burner means to produce a conductance having the characteristic of normally fluctuating in magnitude, means in contact with said conductance at displaced positions and constituting terminals thereof, a device operable in one sense indicating the presence of fluctuations in magnitude of said conductance and one condition of operation of said burner and operable in another sense indicating the absence of fluctuations in magnitude of said conductance and another condition of operation of said burner, a source of electrical energy, an electric circuit for operating said device in said one sense in response to the presence of fluctuations in the magnitude of said conductance including an electric discharge device having an input circuit and an output circuit, a connection between said output circuit and said first mentioned device including said source of energy, and means including a connection to said conductance through said terminals to control the input circuit of said discharge device in response to the presence of fluctuations in the magnitude of said conductance.

11. In combination, fuel burner means to produce a conductance having the characteristic of normally fluctuating in magnitude, means in contact with said conductance at displaced positions and constituting terminals thereof, a device operable in one sense indicating the presence of fluctuations in magnitude of said conductance and one condition of operation of said burner and operable in another sense indicating the absence of fluctuations in magnitude of said conductance and another condition of operation of said burner, a source of electrical energy, an electric circuit for operating said device in said one sense in response to the presence of fluctuations in the magnitude of said conductance including an electric discharge device having an input circuit and an output circuit, a connection

75 between said output circuit and said first mentioned device including said source of energy, a reactance, and means including said reactance and a connection to said conductance through said terminals to control the input circuit of said discharge device in response to the presence of fluctuations in the magnitude of said conductance.

12. In combination, fuel burner means to produce a conductance having the characteristic of normally fluctuating in magnitude, means in contact with said conductance at displaced positions and constituting terminals thereof, a device operable in one sense indicating the presence of fluctuations in magnitude of said conductance and one condition of operation of said burner and operable in another sense indicating the absence of fluctuations in magnitude of said conductance, and another condition of operation of said burner, a source of electrical energy, an electric circuit for operating said device in said one sense in response to the presence of fluctuations in the magnitude of said conductance including an electric discharge device having an input circuit and an output circuit, a connection between said output circuit and said first mentioned device including said source of energy, a second electric discharge device having an input circuit and an output circuit, a connection between the output circuit of said second mentioned discharge device and the input circuit of said first mentioned discharge device including said source of energy and means including a connection to said conductance through said terminals to control the input circuit of said second mentioned discharge device in response to the presence of fluctuations in the magnitude of said conductance.

13. In combination, fuel burner means to produce a conductance having the characteristic of normally fluctuating in magnitude, means in contact with said conductance at displaced positions and constituting terminals thereof, a device operable in one sense indicating the presence of fluctuations in magnitude of said conductance and one condition of operation of said burner and operable in another sense indicating the absence of fluctuations in magnitude of said conductance and another condition of operation of said burner, a source of electrical energy, an electric circuit for operating said device in said one sense in response to the presence of fluctuations in the magnitude of said conductance including an electric discharge device having an input circuit and an output circuit, a connection between said output circuit and said first mentioned device including said source of energy, a second electric discharge device having an input circuit and an output circuit, a connection between the output circuit of said second mentioned discharge device and the input circuit of said first mentioned discharge device including said source of energy, a reactance and a connection to said conductance through said terminals, and means including said reactance to control the input circuit of said second mentioned discharge device in response to the presence of fluctuations in the magnitude of said conductance.

14. In combination, fuel burner means to produce a conductance having the characteristic of normally fluctuating in magnitude, means in contact with said conductance at displaced positions and constituting terminals thereof, a device operable in one sense indicating the presence

of fluctuations in magnitude of said conductance and one condition of operation of said burner and operable in another sense indicating the absence of fluctuations in magnitude of said conductance and another condition of operation of said burner, a source of electrical energy an electric circuit for operating said device in said one sense in response to the presence of fluctuations in the magnitude of said conductance including an electric discharge device having an input circuit and an output circuit, a connection between said output circuit and said first mentioned device including said source of energy, a second electric discharge device having an input circuit and an output circuit, a reactance, a connection between the output circuit of said second mentioned discharge device and the input circuit of said first mentioned discharge device including said reactance and said source of energy, and means including a connection to said conductance through said terminals to control the input circuit of said second mentioned discharge device in response to the presence of fluctuations in the magnitude of said conductance.

15. In combination, fuel burner means to produce a conductance having the characteristic of normally fluctuating in magnitude, means in contact with said conductance at displaced positions and constituting terminals thereof, a device operable in one sense indicating the presence of fluctuations in magnitude of said conductance and one condition of operation of said burner and operable in another sense indicating the absence of fluctuations in magnitude of said conductance and another condition of operation of said burner, a source of electrical energy, an electric circuit for operating said device in said one sense in response to the presence of fluctuations in the magnitude of said conductance including an electric discharge device having an input circuit and an output circuit, a connection between said output circuit and said first mentioned device including said source of energy, a second electric discharge device having an input circuit and an output circuit, a reactance, a connection between the output circuit of said second mentioned discharge device and the input circuit of said first mentioned discharge device including said reactance and said source of energy, a second reactance, and means including said second reactance and a connection to said conductance through said terminals to control the input circuit of said second mentioned discharge device in response to the presence of fluctuations in the magnitude of said conductance.

16. In combination, fuel burner means to produce a varying conductance, means in contact with said conductance at displaced positions and constituting terminals thereof, a device adapted to be positioned in accordance with the amplitude of variation of said conductance to determine the condition of operation of said burner means, a source of electrical energy, an impedance, an electric discharge device having an input circuit and an output circuit, a connection between said output circuit and said device including said source of energy, a connection between said impedance and said input circuit, and means including a connection to said conductance through said terminals for producing a varying potential across said impedance substantially in proportion to the variations of said conductance.

17. In combination, fuel burner means to

produce a varying conductance, means in contact with said conductance at displaced positions and constituting terminals thereof, a device adapted to be positioned in accordance with the amplitude of variation of said conductance to determine the condition of operation of said burner means, a source of electrical energy, an impedance, an electric discharge device having an input circuit and an output circuit, a connection between said output circuit and said device including said source of energy, a connection between said impedance and said input circuit, and means including a reactance and a connection to said conductance through said terminals for producing a varying potential across said impedance substantially in proportion to the variations of said conductance.

18. In combination, fuel burner means to produce a varying conductance, means in contact with said conductance at displaced positions and constituting terminals thereof, a device adapted to be positioned in accordance with the amplitude of variation of said conductance to determine the condition of operation of said burner means, a source of electrical energy, an electric discharge device having an input circuit and an output circuit, a connection between said output circuit and said device including said source of energy, a second electric discharge device having an input circuit and an output circuit, a connection between the output circuit of said second mentioned discharge device and the input circuit of said first mentioned discharge device including said source of energy, and means connected to the input circuit of said second mentioned discharge device and including a connection to said conductance through said terminals to control the conductivity of said second mentioned discharge device substantially in proportion to the variations of said conductance.

19. In combination, fuel burner means to produce a varying conductance, means in contact with said conductance at displaced positions and constituting terminals thereof, a device adapted to be positioned in accordance with the amplitude of variation of said conductance to determine the condition of operation of said burner means, a source of electrical energy, an electric discharge device having an input circuit and an output circuit, a connection between said output circuit and said device including said source of energy, a second electric discharge device having an input circuit and an output circuit, a connection between the output circuit of said second mentioned discharge device and the input circuit of said first mentioned discharge device including said source of energy, a reactance and a connection to said conductance through said terminals, and means including said reactance and connected to the input circuit of said second mentioned discharge device to control the conductivity of said second mentioned discharge device substantially in proportion to the variations of said conductance.

20. In combination, fuel burner means to produce a varying conductance, means in contact with said conductance at displaced positions and constituting terminals thereof, a device adapted to be positioned in accordance with the amplitude of variation of said conductance to determine the condition of operation of said burner means, a source of electrical energy, an electric discharge device having an input circuit and an output circuit, a connection between said output circuit and said device

- including said source of energy, a second electric discharge device having an input circuit and an output circuit, a reactance, a connection between the output circuit of said second mentioned discharge device and the input circuit of said first mentioned discharge device including said reactance and said source of energy, and means connected to the input circuit of said second mentioned discharge device and including a connection to said conductance through said terminals to control the conductivity of said second mentioned discharge device substantially in proportion to the variations of said conductance.
21. In combination, fuel burner means to produce a varying conductance, means in contact with said conductance at displaced positions and constituting terminals thereof, a device adapted to be positioned in accordance with the amplitude of variation of said conductance to determine the condition of operation of said burner means, a source of electrical energy, an electric discharge device having an input circuit and an output circuit, a connection between said output circuit and said device including said source of energy, a second electric discharge device having an input circuit and an output circuit, a reactance, a connection between the output circuit of said second mentioned discharge device and the input circuit of said first mentioned discharge device including said reactance and said source of energy, a second reactance, and means including said second reactance and a connection to said conductance through said terminals and connected to the input circuit of said second mentioned discharge device to control the conductivity of said second mentioned discharge device substantially in proportion to the variations of said conductance.
22. A safety control system for a fuel burner including means to establish a flame at said burner, and a device to control said means comprising in combination, a pair of spaced electrodes insulated from each other and positioned in the path of said flame, a device for operating said control device, a circuit adapted to connect said operating device to a source of electrical energy, and means to control the conductivity of said circuit in response to fluctuations in the conductance between said electrodes to maintain said first mentioned means in flame producing condition.
23. A safety control system for a fuel burner including means to establish a flame at said burner, and a device to control said means comprising in combination, a pair of spaced electrodes insulated from each other and positioned in the path of said flame, and means responsive to fluctuations in the conductance between said electrodes to control said device to maintain said first mentioned means in a flame producing condition.
24. A combined safety and quality control system for a fuel burner including fuel and air supply means and igniting means to establish a flame at said burner comprising in combination, a device to control said fuel supply means, means to control the mixture of fuel and air supplied to said burner, and means responsive only to sustained fluctuations in a characteristic of said flame indicative of flame presence and combustion quality to control said control device and said mixture control means.
25. A combined safety and quality control system for a fuel burner including fuel and air supply means and igniting means to establish a flame at said burner comprising in combination, a device to control said fuel supply means, means to control the mixture of fuel and air supplied to said burner, and means responsive only to sustained fluctuations in a characteristic of said flame indicative of flame presence and combustion quality to control said control device and said mixture control means.
26. A safety system for a fuel burner including means to establish a flame at said burner comprising in combination, a device to control said means, and means responsive only to sustained fluctuations in a characteristic of said flame indicative of flame presence to control said device to maintain said first mentioned means in a flame producing condition.
27. A safety system for a fuel burner including means to establish a flame at said burner, and means responsive only to sustained fluctuations in a characteristic of said flame indicative of flame presence to control said flame establishing means.
28. A safety system for a fuel burner including means to establish at said burner a flame having a fluctuating characteristic indicative of flame presence, and means responsive only to sustained fluctuations in said characteristic and including a device exposed to the region normally including said flame to operate said system to control said flame establishing means and thereby the presence of a flame at said burner.
29. A combustion control system for a fuel burner including means for producing combustion to establish a flame at said burner, and means responsive only to sustained fluctuations in a characteristic of said flame indicative of normal combustion to control said combustion producing means.
30. A combustion control system for a fuel burner including means for producing combustion to establish a flame at said burner, comprising in combination, a pair of spaced electrodes insulated from each other and positioned in the path of said flame, and means connected to said electrodes and responsive to sustained fluctuations in the conductivity of said flame but insensitive to steady values thereof to control said combustion producing means.
31. Apparatus comprising a burner, means for supplying the elements of combustion to the burner, and means responding to the ratio between the elements of combustion supplied to the burner comprising means responsive to changes in the amplitude of fluctuation in the electrical conductivity of the flame issuing from the burner and produced by the burning of the elements of combustion.
32. Apparatus comprising a burner, means for supplying fuel and air to the burner, and means responding to the ratio between the fuel and air supplied to the burner comprising a pair of spaced electrodes disposed to be enveloped in the flame issuing from said burner, an electric circuit including said electrodes, and means responding to changes in the amplitude of fluctuation in the conductivity of said circuit.
33. Apparatus comprising a burner, means for supplying fuel and oxygen to the burner, and means responding to the ratio between the fuel and oxygen supplied to the burner comprising an electric circuit including a portion of the flame produced by the burning of the fuel and oxygen, and means responding to changes in the ampli-

tude of fluctuation in the electrical conductivity of said circuit.

34. Apparatus comprising a burner, means for supplying the elements of combustion to the burner, and means responding to the ratio between the elements of combustion comprising an electric circuit including a portion of the flame produced by the burning of the elements of combustion, and means responding to changes in the amplitude of fluctuation in the electrical conductivity of said circuit.

35. In combination, a furnace, means for supplying the furnace with the elements of combustion, means responding to changes in the amplitude of fluctuation in the electrical conductivity of the flame produced by the combustion of the elements of combustion, and means for controlling the ratio between the elements of combustion supplied the furnace in correspondence with the changes in amplitude of fluctua-

tion in the electrical conductivity of the flame.

36. The method of maintaining a desired fuel-air ratio to a furnace which includes increasing and decreasing the fuel-air ratio in correspondence with the decreases and increases, respectively, in the amplitude of fluctuation in the electrical conductivity of the flame produced by burning of the fuel and air.

37. The method of obtaining response to the ratio between the elements of combustion supplied a flame which includes obtaining response to changes in the amplitude of fluctuation in the electrical conductivity of the flame resulting from the combustion of the elements.

38. The method of obtaining response to the completeness of combustion which includes obtaining response to changes in the amplitude of fluctuation in the electrical conductivity of the flame produced by such combustion.

WALTER P. WILLS.
